SLITTING MACHINE

Leland S. Rosener, San Francisco, Calif., assignor,
by mesne assignments, to Fibreboard Products
Inc., San Francisco, Calif., a corporation of
Delaware

Application July 6, 1926. Serial No. 120,616

24 Claims. (Cl. 164—60)

My invention relates to mechanism for splitting a sheet of material into strips of predetermined width and one of the objects of the invention is the provision of a machine for splitting into narrower strips a relatively wide strip or web of paper or fiber board.

Another object of the invention is the provision of a machine of the character described which may be quickly and readily brought into accurate adjustment and which embodies various refinements of setting and adjustment so that its use is economical and convenient.

Another object of the invention is the provision of a slitting machine of the character described having a large capacity and which may be set in the line between the silicate rolls and the transverse cutting machine, to cooperate with the latter in reducing the relatively wide web of layered paper board to pieces of definite width and length.

My invention possesses other objects and features of advantage some of which with the foregoing will be set forth in the following description of my invention which is illustrated in the drawings forming part of the specification. I do not limit myself to the showing made by the said description and drawings as I may adopt variant forms of my invention within the scope of the claims.

Referring to the drawings:

Figures 1a and 1b together constitute a plan view of my slitting machine; and Figure 2 is an end elevation, the direction of the view being indicated by the arrow 2 in Figure 1b. Figures 3a and 3b together constitute a front elevation of my slitting machine, a portion of the structure in Figure 3b being shown as broken away to disclose the underlying parts. Figure 4 is a detail in side elevation, showing the adjustable frames of my device. Figure 5 is a transverse vertical sectional view taken thru a portion of the structure shown in Figure 3b in which figure the plane of section is indicated by the line 5—5.

In broadly descriptive terms, the slitting machine of my invention comprises a table provided with a number of slideways, in each of which is disposed at least one and preferably two independently adjustable units, each comprising a frame in which two slitting cutters are mounted together with means for adjusting one of the cutters relative to the other and means for rotating the cutters. A calibrated scale is arranged in connection with each slideway and means are provided for the accurate setting of each of the units in accordance with the desired scale reading so that the distances between the several cutters may

be very closely regulated to cut the web into strips which are accurately sized. Since there is always more or less transverse weaving or shifting of the web as it leaves the squeeze rolls after passing thru the silicate rolls, means are provided for a compensating movement of the entire table.

More particularly my slitting machine comprises a table 2 carried on the pivotally arranged legs 3 and thereby adapted to adjustment in a direction transverse to the web of material fed across the table. This adjustment is controlled by a screw spindle 4 threaded thru a pivotally mounted nut 6 arranged in the wall or other fixed structure 7 and at its other end being journaled in the pivotally mounted nut 8 arranged in one end of the table. One end of the spindle is provided with a sprocket wheel 9 over which runs a chain 11 with which the spindle may be turned. It is contemplated that the upper surface of the table over which the web passes will be well elevated above the floor and therefore the chain 11 extends downwardly a sufficient distance so as to be readily accessible for a workman below the table.

The table is formed with a plurality of slide-ways 12; and in the present example, there are shown three such slideways. In each of these slideways is mounted for slidable movement therein, a cutting unit, of which the main casting is shown in Figure 4. This casting comprises a main frame body 13 provided with slides or flanges 14 adjusted to form a sliding fit in the slideways 12 with the upper surface of the main body 13 substantially flush with the top of the table as indicated in Figure 3b. Extending from one end of the body 13 is the cantilever arm 16 provided at its end with a vertical slideway 17 in which is slidably mounted a block 18, provided with an adjusting screw 19 operated by the hand wheel 21. The block is fixed in position after adjustment by the nuts 22.

The block 18 is provided at its lower end with a bearing 23 in which is journaled a shaft 24, and in the base of the cantilever arm is arranged a bearing 26 in which is journaled a shaft 27 connected to the shaft 24 by the shaft 28 and universal joints 29 and 31. The universal joint 31 is splined upon the end of the shaft 24 so as to permit axial movement therebetween, and axial adjustment of the shaft 24 is secured by a clamp collar 32 threaded upon one side of the bearing 23 and embodying a groove in which is seated a flange 33 which is fixed on the shaft 24. On the outer end of the shaft 24 is fixed a cutting blade 34 preferably having a beveled edge as shown. It

will be seen from the above that the cutting blade 5 may be accurately positioned by loosening the clamp collar 32 and rotating it to move the shaft 24 to the desired position, in which it may be 5 securely held by tightening the clamp screw of the collar 32.

Disposed in the base portion of the frame are the bearings 36 and 37 in which is journaled a shaft 38 on the outer end of which is also fixed a cutting blade 39. The shaft 38 is journaled so that no axial movement occurs and the diameter of the cutting blade is such that the periphery extends slightly above the plane of the table top so as to cut thru the material passing thereover. 10 In working relation the upper cutter 34 is adjusted axially so that it laps over the lower cutter 39 slightly, the bevel on the blades being in the opposite direction so that both blades cut on the same line in opposition to each other. The 15 clamp collar 32 for axial adjustment and the adjusting screw 19 for vertical adjustment permit the closest regulation of the upper cutter 34 with respect to the lower cutter 39, so that by their mutual action a single slit is formed in the 20 material passing over the table top and between the two blades of the unit.

By reference to the plan view in Figures 1a and 1b it will be noted that in each slideway 12 there are two frames or units of the character 30 just described and that these units are so arranged that the cantilever arms are pointing toward each other in each way. It will also be noted that some of the frames are long and some relatively short; and this of course is done to 35 facilitate placing the cutting blades in the desired positions so that on wide webs each pair of cutting blades is given its maximum range to permit the cutting of the web into strips of any desired width or into strips the width of each of 40 which is different than the other strip.

Unitary means are provided in each unit for driving the shafts 27 and 38, these shafts being connected for rotation together by the gears 41. Also fixed on the upper shaft 27 is a gear 42 connected by gears 43 with the gear 44 on the shaft 45 of the motor 46, which thus drives the cutter shafts thru a gear train providing the desired reduction in speed.

Means are provided for calibrating the positions of each of the units with reference to the other units and for accurately setting and then holding each pair of cutters in the desired position. Extending longitudinally across the table within each slideway is a bar 51 conveniently 50 formed of a piece of angle iron, the vertical flange of which is finished and provided with graduations 52. Each of these bars is carefully prepared and set so that the corresponding graduations on all of the bars are in line. Releasably 55 secured by the screws 53 to the bottom of each unit frame adjacent one end is an angle block 54 having a threaded extension 56 adapted to pass thru the lug 57 projecting from the bottom 60 of the frame and to be fixed in the lug by the adjusting nut 58 on either side thereof. Threaded into the angle piece 54 is a screw 59 provided with a shoe 61 adapted to engage the scale bar 51. In order to prevent deflection of the scale bar under the pressure of the screw 59 a backing 65 flange 62 is fixed on the angle piece 54 to extend downwardly behind the scale bar and furnish it support. Also fixed on the angle piece 54 is a handle 63, by which the frame may be moved along the slideway when the screw 59 is loosened. 70 The upper vertical edge of this handle together

with the adjacent vertical edge of the angle piece 54, is squared off to provide a pointer edge 64 for setting on the graduations of the scale bar. An upwardly extending lug 66 is also provided, the face of which is vertically aligned with the 80 pointer edge. In order to place each frame in proper position, the screw 59 is loosened to release the shoe from the scale bar and permit the sliding of the frame to approximate position. The 85 screws 53 are next loosened slightly and also the nut 58 so that the pointer edge 64 may be located exactly over the required graduation. The screw 59 is then tightened up to clamp the angle piece 54 on the scale bar, and by adjustment of the nut 58 the frame is moved so as to bring the 90 lower cutter 39 back closely adjacent the lug 66, at which time the screws 53 are again tightened. If this operation has been carefully attended to the cutting edge of both cutters are vertically aligned with the pointer edge 64 and the desired 95 marking on the scale bar. Each of the units may be thus adjusted to the desired positions with the cutters accurately placed so that in a machine similar to that illustrated in the drawings and having three ways each with two units, the 100 web may be trimmed on the edges and slit into five strips, of the same or different width, and all in the same operation.

I claim:

1. A slitting machine comprising a table, a 105 frame movably disposed on said table, a pair of shafts journaled in said frame, cutters arranged on said shafts, means for driving said shafts, and means for adjusting said table in directions axially of said shafts.

2. A slitting machine comprising a table, a frame slidably mounted on said table and including a cantilever arm, a bearing mounted on said cantilever arm for movement thereon toward and from the body of the frame, a shaft journaled 115 in the frame body, a second shaft journaled in the movable bearing, cooperating cutters fixed for rotation with said shafts, and means for rotating said shafts.

3. A slitting machine comprising a table, a 120 frame slidably mounted on said table and including a cantilever arm, a bearing mounted on said cantilever arm for movement toward and from the body of the frame, a shaft journaled in the frame body, a second shaft journaled in the 125 movable bearing, cooperating cutters fixed for rotation with said shafts, a third shaft journaled on said cantilever arm, unitary means for driving the first and third shafts, and a universal coupling means connecting the second and third 130 shafts.

4. A slitting machine comprising a table having a plurality of slideways, a frame slidably mounted in each slideway, a pair of tangentially cooperating circular cutters journaled in each 135 frame and approximately tangent to the plane of the table, and means for rotating the cutters.

5. A slitting machine comprising a table having a plurality of slideways, a pair of frames 140 slidably mounted in each slideway, each frame including a cantilever arm extending toward the arm of the companion frame above the plane of the table, a pair of tangentially cooperating circular cutters journaled in each frame and approximately tangent to the plane of the table, 145 one of said cutters being on the body of the frame and the other on the cantilever arm, and means for rotating the cutters.

6. A slitting machine comprising a table having a plurality of slideways, a pair of frames 150

- slidably mounted in each slideway, each frame including a cantilever arm extending toward the arm of the companion frame above the plane of the table, a pair of tangentially cooperating 5 circular cutters journaled in each frame and approximately tangent to the plane of the table, one of said cutters being on the body of the frame and the other on the cantilever arm, a scale for evaluating the position of each pair of 10 cutters, and means for rotating the cutters.
7. A slitting machine comprising a table having a plurality of slideways, a pair of frames slidably mounted in each slideway, each frame including a cantilever arm extending toward the 15 arm of the companion frame above the plane of the table, a pair of tangentially cooperating circular cutters journaled in each frame and approximately tangent to the plane of the table, one of said cutters being on the body of the frame and the other on the cantilever arm, means for 20 radially adjusting one of the cutters on each frame relative to the other, and means for rotating the cutters.
8. A slitting machine comprising a table having a slideway therein, a frame movable in said 25 slideway and having a cantilever arm extending above the table, a bearing slidably mounted on said cantilever arm for movement toward and from the table, a shaft journaled in said frame, a second shaft journaled in said movable bearing, means for rotating said shafts, and tangentially cooperating circular cutters fixed for 30 rotation with said shafts and approximately tangent to the plane of the table.
9. A slitting machine comprising a table, a slitting unit frame slidably mounted on said 35 table, a scale bar fixed on said table, a block having a pointer edge and adjustably arranged on said frame, said block being slidable along said 40 scale bar, and means for clamping the block to the scale bar.
10. A slitting machine comprising a table, a plurality of pairs of slitting unit frames slidably arranged on said table, a graduated scale bar 45 fixed on the table adjacent each pair of frames, said bars having their corresponding graduations in alinement, a block having a pointer edge and adjustably arranged on each frame, and means for clamping each block to its associated scale 50 bar.
11. A slitting machine comprising a table, a slitting unit frame slidably mounted on said table, a pair of cutters journaled for tangential cooperation in said frame, a scale bar fixed on said table adjacent said frame, a block having 55 a pointer edge, means for clamping the block at desired positions against said scale bar, and means interposed between frame and block for adjusting the frame to aline the cutters with the 60 pointer edge of the block.
12. A slitting machine comprising a table pivotally mounted for movement in a direction transverse of a web of material to be slit, a frame movably disposed on said table, a pair of shafts journaled in said frame, cutters arranged on said shafts, means for driving said shafts, and means for adjusting said table in directions axially of 65 said shafts.
13. A slitting machine comprising a table pivotally mounted for movement in a direction transverse of a web of material to be slit, a frame movably disposed on said table, a pair of shafts journaled in said frame, cutters arranged on said shafts, means for driving said shafts, a fixed 70 element, and means interposed between the fixed element and table for varying the distance therebetween and thereby move the table transversely of the web.
14. In a multiple shear, a plurality of pairs of oppositely arranged shears positioned side by side, so as to simultaneously engage material, each shear comprising a pair of cooperating cutters and each pair of shears being relatively stationary with respect to another pair of shears, but each shear in a pair being adapted for movement relative to the other shear in such pair, and a single feed means arranged to carry material to the several pairs of shears. 80
15. In a multiple shear, a plurality of pairs of oppositely arranged shears positioned side by side, so as to simultaneously engage material, each shear comprising a pair of cooperating cutters and each pair of shears being relatively stationary with respect to another pair of shears, but each shear in a pair being adapted for movement relative to the other shear in such pair. 90
16. A slitting machine comprising a table, a slitting unit frame slidably mounted on said table, a scale bar fixed on said table, a block having a pointer edge and adjustably arranged on said frame, said block being slidable along said scale bar, means for clamping the block to the scale bar, and means for adjusting the relative position between the block and frame after the block is clamped. 95
17. In a multiple shear, a plurality of pairs of oppositely arranged frames positioned side by side, a plurality of cooperating cutters mounted on each frame so as to simultaneously engage material, each pair of frames being relatively stationary with respect to another pair of frames, but each frame in a pair being adapted for movement relative to the other frame in such pair. 110
18. In a multiple shear, a table, a plurality of frames movably disposed on said table, a plurality of cutters mounted on each frame so as to simultaneously engage material, a motor upon each frame and movable therewith, and independent driving means connecting the motors with the cutters upon corresponding frames. 115
19. In a multiple shear, a table, a plurality of rows of frames, the frames of each row being arranged in tandem and movably disposed on said table, a plurality of cutters mounted on each frame so as to simultaneously engage material, a motor upon each frame and movable therewith, and independent driving means connecting the motors with the cutters upon corresponding frames. 125
20. A slitting machine comprising a frame, a pair of shafts journaled in said frame, universal joints interposed in one of said shafts, cutters arranged on said shafts, means for driving said shafts, means for moving a portion of the jointed shaft from and toward the other, and means for axially adjusting one of said shafts relative to the other. 135
21. A slitting machine comprising a frame, a pair of shafts journaled in said frame, universal joints interposed in one of said shafts, cutters arranged on said shafts, means for driving said shafts, means for moving a portion of the jointed shaft from and toward the other, and means for axially adjusting the cutter on the jointed shaft relative to the other cutter. 140
22. A slitting machine comprising a table, a frame disposed on said table, a shaft journaled in said frame, a cutter arranged on said shaft, means for driving said shaft, and means for ad- 150

justing said table in directions axially of said shaft.

23. A slitting machine comprising a table, a plurality of pairs of slitting unit frames movably arranged on said table, a graduated scale fixedly mounted adjacent each pair of frames, said scales having their corresponding graduations in alignment, a pointer mounted on each frame, and means for clamping each frame in desired position.

24. In a multiple shear, a plurality of pairs

of oppositely arranged frames positioned side by side, a plurality of cutters on each frame and mounted to provide a shear on said frame, so as to simultaneously engage material, each pair of frames and the shears thereon being relatively stationary with respect to another pair of frames, but each frame in each pair and the shear thereon being mounted for movement toward and from the other frame in such pair.
